UNITED STATES PATENT OFFICE

HILDA A. KROGSTAD, OF KNOX, NORTH DAKOTA

HEN'S NEST

Application filed June 24, 1929. Serial No. 373,405.

This invention appertains to nests for fowls and has for one of its primary objects to provide a sanitary nest, which is so constructed that the same can be kept and maintained in a clean condition at all times, in an easy and effective manner.

A further object of my invention is to provide an all metal hen's nest having guides therein for slidably receiving drawers forming the nests proper, whereby the drawers can be conveniently removed from the frame or casing of the nest to permit the expeditious cleaning thereof.

A further object of my invention is the provision of novel means for forming the frame or casing of the nest so as to insure the proper ventilation thereof at all times with means for suspending the nest in spaced relation to the wall of the henhouse or other support whereby ventilation of the nest in rear will be had and whereby the propagation of vermin between the nest and support will be prevented.

A further object of my invention is the provision of novel means for forming the frame or casing of the nest whereby an exceptionally simple and durable structure will be had and which will be easy and cheap to manufacture and thus be enabled to be placed upon the market at a reasonable cost.

A still further object of my invention is the provision of novel perches for the nest, the perches forming means for bracing the frame or casing of the nest.

With these and other objects in view, the invention consists in the novel construction, arrangement and formation of parts, as will be hereinafter more specifically described, claimed, and illustrated in the accompanying drawings, in which drawings:

Figure 1 is a side elevation of my improved nest showing the same suspended from a wall or other support, the wall or other support being shown in vertical section;

Figure 2 is a front elevation of my improved nest;

Figure 3 is a vertical fragmentary central section through the nest taken on the line 3—3 of Figure 2 looking in the direction of the arrows, and

Figure 4 is a horizontal section through the nest taken on the line 4—4 of Figure 2 looking in the direction of the arrows.

Referring to the drawings in detail, wherein similar reference characters designate corresponding parts throughout the several views, the letter A generally indicates my improved nest and B the wall of a henhouse or other support from which the nest A can be suspended.

The nest A comprises a novel all metal frame or casing 10 which includes like spaced side walls 11 and 12, the forward edges of which are provided at spaced points with pairs of bendable tongues 13, the purpose of which will be later described. The rear edges of the side walls 11 and 12 can have formed thereon or secured thereto laterally extending notched supporting lugs 14 which form means for permitting the device to be suspended from the support B, as also will be later described.

The upper edges of the side walls 11 and 12 are preferably inclined downwardly and forwardly and form a seat for the reception of the top wall 15 and owing to the inclination of the top edges of the side walls, the top wall 15 is pitched downwardly, as shown in the drawings. This top wall 15 can be secured in place in any desired way, such as by the use of angle iron straps or brackets 16 which are riveted respectively to the side walls 11 and 12 and top wall 15.

The front wall 17 of the frame or casing is provided adjacent to its side edges with spaced slots 18 for the reception of the pairs of bendable tongues 13 and the tongues of each pair of tongues are bent in opposite directions, as shown in Figure 2 of the drawings, in order to hold the front wall in proper position against accidental displacement. This front wall 17 is provided with upper and lower enlarged entrance openings 19 and 20 which permit the entrance and exit of the hen into the nest.

Riveted or otherwise secured to the inner faces of the side walls 11 and 12 directly below each entrance opening 19 and 20 are angle iron supporting members 21, which constitute guides and supports for the nests proper.

22. The nests proper 22 are in the nature of drawers and are also formed from sheet metal and each includes a bottom wall 23, side walls 24, a front wall 25 and a rear wall 26. It is 5 to be noted that the rear wall 26 of each nest proper extends a considerable distance above the side walls 24 and the front wall 25, but terminates short of the angle iron guides and supports 21 and the top wall 15, in order to 10 form an opening or slot 27 to permit the passage of air into the casing above each nest proper. The front walls 25 of the nests proper 22 have secured thereto drawer pulls 28 so that the nests proper can be conveniently 15 removed from the casing of the nests both for the purpose of cleaning and for facilitating the removal of the eggs from the nests.

Disposed below each opening 19 and 20 and in front thereof is a transversely extending 20 perch 29 and each perch has its terminals secured to rearwardly extending brace rods 30, the rear ends of which are angled upwardly toward the rear of the frame or casing of the nest and the angled ends 31 are riveted or 25 otherwise secured to the side walls of the frame or casing and constitute braces therefor.

At this point it is to be noted that the entire 30 rear of the casing or frame 10 of the nest is left open and that the same is merely closed by the rear walls 26 of the nests proper 22 and that an unobstructed ventilation is had through the nests by means of the entrance openings 19 and 20 and the spaces above the 35 upper edges of the rear walls 26 of the nests proper.

In accordance with my invention I provide 40 means for suspending the device A in spaced relation to the wall or support B and thus the wall or support B has secured thereto pairs of upper and lower supporting hooks 32 which are provided with relatively deep depending bills 33 and the slotted ears or lugs 14 of the frame or casing 10 of the nest are hooked over 45 the bills 33 and due to the spacing of the bills of the hooks from the support or wall B, the entire nest is arranged in spaced relation to the wall or support, thereby permitting ventilation to be had in rear of the nest as well as 50 preventing the propagation of vermin between the nest and the support.

Due to the arrangement of the hooks 32 and the notched ears or lugs 14, the nest can be readily placed in position on the support or 55 removed therefrom when necessary or desirable.

Changes in details may be made without departing from the spirit or the scope of this invention, but:

60. What I claim as new is:

A sanitary hen's nest comprising a casing having an open back, a front wall provided with an entrance opening, and a drawer slidably mounted within the casing through the 65 entrance opening and provided with a rear

wall extending above the side and front walls thereof and terminating slightly short of the top wall of the casing defining in connection therewith a ventilating opening when the drawer is closed, said rear wall of the drawer constituting means for engaging the front wall of the casing when the drawer is pulled outward to limit the outward sliding movement thereof.

In testimony whereof I affix my signature. 75
Mrs. HILDA A. KROGSTAD.
